UNITED STATES PATENT OFFICE

141,033

DESIGN FOR A GAME BOARD

James Fleisher, Minneapolis, Minn.

Application September 4, 1944, Serial No. 115,185

Term of patent 3½ years

(Cl. D34—5)

To all whom it may concern:

Be it known that I, James Fleisher, a citizen of the United States, and residing in the city of Minneapolis, Hennepin County, State of Minnesota, have invented a new, original, and ornamental Design for a Game Board, of which the following is a specification, reference being had to the accompanying drawing, forming a part thereof, wherein the figure is a top perspective view of a game board showing my new design.

I claim:

The ornamental design for a game board, substantially as shown.

JAMES FLEISHER.
